181,999

COMB

Samuel R. Pruyn, Eagle Rock, Calif.

Application March 22, 1957, Serial No. 45,399

Term of patent 14 years

(Cl. D86—8)

Fig. 4.

Fig. 2.

Fig. 1.

Fig. 3.

Fig. 5.

Figure 1 is a plan view of the comb of the present invention;

Figure 2 is a side edge view taken from the left of the comb of Figure 1;

Figure 3 is a side edge view taken from the right of the comb of Figure 1;

Figure 4 is an end edge view taken from the adjacent end of the comb of Figure 1; and

Figure 5 is an end edge view taken from the comb end adjacent thereto of Figure 1.

I claim:

The ornamental design for a comb, as shown.

References Cited in the file of this patent

FOREIGN PATENTS

145,017 Austria ----- Mar. 25, 1936